UNITED STATES PATENT OFFICE.

CHARLES A. NEEDHAM, OF NEW YORK, N. Y., ASSIGNOR OF ONE-HALF TO
GEORGE G. NEEDHAM, OF NEW YORK, N. Y.

AERIAL DEVICE.

SPECIFICATION forming part of Letters Patent No. 730,956, dated June 16, 1903.

Application filed May 21, 1902. Serial No. 108,302. (No model.)

To all whom it may concern:

Be it known that I, CHARLES A. NEEDHAM, a citizen of the United States, and a resident of the borough of Manhattan, in the city and 5 State of New York, have invented a new and useful Aerial Device, of which the following is a specification.

My invention consists in aerial devices in which means are provided for supporting 10 persons comfortably from hangers fitted to travel along an elevated way or track.

One object of my invention is to provide a device of the above character in which the body of the person is supported yieldingly 15 by a main spring and the limbs are supported by auxiliary springs of much less tension, so as to permit the person to easily assume different positions in the air as the hanger travels along the elevated way or track and to exercise 20 the different limbs, if so desired.

A further object is to provide an aerial device in which the person supported by the hanger may propel the same along the elevated way or track at any desired speed by 25 his own exertions.

A still further object is to provide certain improvements in the construction, form, and arrangement of the several parts whereby the device is rendered simple and effective.

30 A practical embodiment of my invention is represented in the accompanying drawings, in which—

Figure 1 represents a manually-propelled aerial device embodying my invention in side 35 elevation, a portion of the elevated way or track being broken away to show more clearly the parts carried thereby, a person being shown supported by the hanger. Fig. 2 is a transverse section through the device shown 40 in Fig. 1. Fig. 3 is an enlarged detail view showing the interior arrangement of one of the traction-wheels of the hanger and showing the pawl-and-ratchet connection between the axle and the wheel. Fig. 4 is a side view of 45 a modified form of aerial device, all of the limbs being yieldingly supported by auxiliary springs of lighter tension than the body-supporting spring. Fig. 5 is a transverse section through the elevated way shown in Fig. 4 and 50 the hanger used therewith. Fig. 6 is a side view of a modified form of aerial device in

which a single track only is utilized. Fig. 7 is a transverse section showing more clearly the hanger for use in connection with the single track or cable; and Fig. 8 is a view in side 55 elevation of another modified form of aerial device, which is more particularly adapted for ladies' use, in which the auxiliary springs for supporting the legs of the person are provided with stirrups instead of rings. 60

Proceeding to describe in detail the device shown in Figs. 1, 2, and 3, the elevated way or track is provided with two rails 1 and 2, which are formed on inwardly-extended branches 3 and 4 of a U-shaped beam 5. The 65 hanger is denoted by 6, and it is provided with two pairs of wheels arranged to travel along the rails 1 and 2 of the track. In the form shown herein the rear wheels 8 are free to travel along the tracks, while the front 70 wheels 7 are used as driving-wheels for propelling the hanger along the track. The spring for yieldingly supporting the body of the person is denoted by 9, one end of which is secured to the hanger 6 and the other end 75 of which is provided with an extended sling 10, which is arranged to embrace the body portion of the person for a sufficient distance to comfortably support the person. In the present instance I have shown the sling as 80 removably secured to the spring by means of a snap-hook 11, carried by the lower end of the spring, the sling 10 being provided at its end with gromets 12, fitted to be engaged by the snap-hook 11. The lower limbs of the 85 person are supported by means of auxiliary springs 13 14 of considerably less tension than the spring 9, so as to permit a free action of the said limbs. The lower ends of these auxiliary springs 13 14 are preferably provided with rings 15 and 16 for embracing the ankles of the person supported by the hanger. The hanger is propelled by the person supported thereby in the following manner: Each of the driving traction- 90 wheels 7 is provided with an annular internal ratchet 17, which is engaged by a spring-actuated pawl 18, carried by a drum 19, loosely mounted on the axle 20 of the said wheel. A retraction-spring 21 is secured at 95 one end to the stationary axle 20 and at its other end to the drum 19 for returning the

drum to its normal position. A strap or cord 22 is passed one or more times around the drum 19 and is then secured to the same. This strap or cord 22 is engaged by an idler pulley 23, secured to the side of the hanger 6 for guiding the strap or cord as it is operated for driving the wheel. The lower ends of the straps or cords 22 are preferably provided with hand-rings 24, which may be 10 grasped by the hands of the person suspended from the hanger for enabling the person to drive the hanger forwardly along the elevated way or track. An overhanging bracket-support 25 for the U-shaped bar 5 of the elevated way or track is provided, which bracket-support may be of any desired form for supporting the way or track at the proper elevation from the ground.

In the form shown in Figs. 4 and 5 the elevated way comprises two cables 26 27, supported by a bracket 28. In this case the hanger 6 is provided with two pairs of loose traction-wheels 7 and 8, which are fitted to travel along the cables 26 27 of the way. 25 This elevated way or track may be so arranged as to cause the hanger 6 to travel along the same by gravity, and the said way or track may also be made undulating, so as to cause the person carried by the hanger to 30 rise and fall as the hanger travels along the said way. In this form the arms, as well as the legs, are supported by auxiliary springs, the springs for supporting the arms being denoted by 29 and 30. These arm-supporting 35 springs are provided with suitable rings 31 32 for engagement by the arms or hands of the person being suspended from the hanger.

In the form shown in Figs. 6 and 7 the elevated way or track comprises a single cable 33, and the hanger 6 is provided with only two traction-wheels 7 and 8, arranged to run loosely along the said cable.

In the form shown in Fig. 8 the single cable 33 is shown as undulating, so as to cause 45 the person to rise and fall as the hanger travels along the same. In this form also the hanger 34 is shown as being provided with a single traction-wheel 35, so as to give the person a swinging movement as well as a 50 yielding up-and-down movement as the hanger travels along the track. In this view the suspension device is shown as more particularly applicable for use of ladies, the rear

auxiliary springs 13 and 14 being provided at their lower ends with stirrups 36 37, which 55 may be caused to engage the knees of the person suspended from the hanger.

It is evident that slight changes might be resorted to in the form, construction, and arrangement of the several parts without departing from the spirit and scope of my invention. Hence I do not wish to limit myself strictly to the structure herein shown and described; but

What I claim is—

1. An aerial device comprising an elevated way or track, a hanger fitted to travel along the same, and means for suspending a person from the hanger comprising a main spring for supporting the body of the person and auxiliary springs for supporting the limbs of the person.

2. An aerial device comprising an elevated way or track, a hanger fitted to travel along the same, and means for suspending a person from the hanger comprising a main spring for supporting the body of the person and auxiliary springs for supporting the legs of the person.

3. An aerial device comprising an elevated way, or track, a hanger fitted to travel along the same, and means for suspending a person from the hanger comprising a main spring for supporting the body of the person and auxiliary springs having attaching devices for engaging the limbs of the person, the said auxiliary springs being of less strength than the main spring to permit the free movement of the limbs of the person.

4. An aerial device comprising an elevated way or track, a hanger fitted to travel along the same, means for suspending a person from the hanger comprising a main spring for supporting the body of the person, auxiliary springs of less tension for supporting the 95 legs of the person and means under the control of the arms of the person for propelling the hanger along the way or track.

In testimony that I claim the foregoing as my invention I have signed my name, in presence of two witnesses, this 17th day of May, 1902.

CHARLES A. NEEDHAM.
